UNITED STATES PATENT OFFICE.

PAUL BATEMAN, OF ST. LOUIS, MISSOURI.

DUMP-CAR.

981,157.

Specification of Letters Patent. Patented Jan. 10, 1911.

Application filed November 22, 1909. Serial No. 529,199.

To all whom it may concern:

Be it known that I, PAUL BATEMAN, a citizen of the United States of America, residing in the city of St. Louis and State of Missouri, have invented certain new and useful Improvements in Dump-Cars, of which the following is a full, clear, and exact description, reference being had to the accompanying drawings, forming part of this specification.

My invention relates to that character of railway cars having openings through which the contents of the cars may be dumped therefrom, and doorways for controlling said openings. It has been a common practice and, in so far as I am aware, a universal practice in constructing cars of this description to provide a means for elevating the dump doors, which is also intended to serve as a means for the support of the doors after they have been elevated or closed. These constructions are objectionable for several reasons, among the most important of which are the following, namely: should the door elevating means become broken, or so impaired as to render it an unfit support for the door upheld thereby in its closed position, the door is permitted to descend, with a resultant discharge of contents of the car. A second objection to supporting the doors by the means provided for elevating them is that, inasmuch as the doors depend for their support upon said elevating means, it is impossible to repair the elevating means in a loaded car, in the event of impairment thereof, without providing a suitable support for any door connected to the impaired elevating means and by which the door may be held in closed position during the period of time required for repair of the door elevating means.

My invention has for its object the provision of means, aside from the door elevating means, which is carried by the frame or body of the car and is adapted to efficiently support the dump door, after it has been elevated by a suitable elevating means and whereby the elevating means is wholly relieved of the office of supporting the door, thus overcoming the objectionable features hereinbefore named.

Figure I is a side elevation of a portion of

a dump car with one of the doors of the car in lowered position. Fig. II is a cross section through the car, with the dump door shown in elevated or closed position in full lines, and in lowered position in dotted lines. Fig. III is a vertical cross section illustrating the dump door in elevated position, and showing the means by which it is carried to the supports provided therefor.

In the accompanying drawings:—A designates the body of the car, at the bottom of which is a suitable underframe, comprising a center sill B, between which and a side wall of the car at the body bottom is an opening C, through which the contents of the car body may be dumped.

D is a dump door that serves as a closure for the opening C when the door is in an elevated position, as seen in full lines Fig. II.

1 designates one of a pair of brackets, (see Fig. II), secured to the center sill B, and by which the door D is pivotally supported at its inner end, the pivotal connection between said brackets and the door being preferably provided through the medium of links 2, each having one of its ends pivoted to the bracket corresponding thereto and its other end pivotally connected in any suitable manner to the dump door. While I prefer to employ the links 2 as a means for providing pivotal connection between the dump door and the supporting means, namely, the brackets 1, it is obvious that other means of pivotal connection between these members may be provided, it being only essential that the door be so pivotally supported at its inner edge as to provide for it being moved transversely of the car, or toward and away from a side of the car.

3 designates a winding shaft mounted in suitable bearings adjacent to a side of the car, and which is adapted to be rotated by any suitable means. This winding shaft is adapted to serve in conjunction with a connection 4, for instance, a chain, as means for elevating the dump door to restore it to a closed position after it has been lowered. One end of the connection 4 is attached to the shaft, preferably by attachment to a grooved drum or member 5, rigid on the shaft, and in the groove, which is preferably a spiral one, (see Fig. I), while the other

end of the connection is preferably secured to a bracket 6 secured to the outer end of the dump door. The winding shaft has fixed to it a pinion 7, (see Figs. I and III), while the dump door is provided with a rack 8 adapted to be engaged by said pinion when the dump door is raised, through the medium of the winding shaft and the connection 4 uniting the dump door to said winding shaft.

9 designates a ledge member, (see Figs. II and III), that is located in proximity to the winding shaft 3, there being preferably two or more of said ledge members at the location of each door opening at the bottom of a car and beneath the outer ends of the door opening. The ledge members 9 are adapted to receive lugs 10 carried by the dump door and located at the outer ends of the door in such positions that when the door has been elevated to position to close the opening in the bottom of the car adapted to be closed thereby, and has been moved outwardly or transversely of the car, said lugs will ride onto the ledge members 9 for the purpose of enabling the ledge members to perform the office of upholding the outer end of the door and without any dependence upon the door elevating means for the support of the door.

It will be apparent that when the dump door is in a closed position and supported by the ledge members 9, it is only necessary, in order that a door may be lowered, to rotate the winding shaft 3 in the proper direction, with the result of causing the pinion 7 carried by the winding shaft to, by co-operation with the rack 8, shift the dump door inwardly toward the center of the car, a shifting that is permitted due to the pivotal support of the inner end of the door; and that when this shifting action has taken place, the lugs 10 carried by the door will travel off of the ledge members 9, thereby permitting descent of the dump door. When the dump door is to be again elevated, the winding shaft is rotated, and the door is elevated through the medium of said winding shaft and the connection 4 until the rack 8 has been moved into engagement with the pinion 7, and the bottoms of the lugs 10 carried by the dump door are raised to the top faces of the ledge members 9. Then, upon continued rotation of the winding shaft, the pinion 7, by co-operating with the rack 8, causes the dump door to be drawn outwardly transversely of the car until the lugs 10 are firmly seated upon the ledge members 9 to support the dump door, irrespective of the means by which the door was moved to its elevated position.

I claim:

1. A car having a dump opening, a door for controlling said opening, supported at

one end for endwise movement, means for lifting said door to an elevated position, and means independent of said lifting means for the support of the free end of the door when the door is in an elevated position.

2. A car having a dump opening, a door for controlling said opening, supported for endwise movement, means for lifting said door to an elevated position, and stationary means independent of said lifting means for the support of the door in an elevated position.

3. A car having a dump opening, a door for controlling said opening pivotally supported at one end for endwise movement, means for lifting said door to an elevated position, and means independent of the said lifting means providing for the support of the free end of the door when the door is in an elevated position.

4. A car having a dump opening, a door supported at one end for endwise movement for control of said opening, means for lifting said door to an elevated position, and a ledge member rigidly supported in the car, aside from said lifting means, and whereby said door is supported in an elevated position independently of said lifting means.

5. A car having a dump opening, a door supported at one end for endwise movement for control of said opening, means for lifting said door to an elevated position, a ledge member rigidly supported in the car, aside from said lifting means, and whereby said door is supported in an elevated position; said door being provided with a member adapted to be shifted onto said ledge member by endwise movement of the door after it has been elevated.

6. A car having a dump opening, a door supported at one end for endwise movement, means for lifting said door to an elevated position, means independent of said lifting means for supporting said door in its elevated position, and means whereby the door is shifted endwise to carry it into a position that will provide for its support by the supporting means independently of the lifting means.

7. A car having a dump opening, a door for controlling said opening, and which is pivotally supported at one end and movable endwise, a shaft having connection with said door and by which the door may be elevated, a rigid support by which said door is upheld in an elevated position, and means for moving said door endwise into position to be upheld by said rigid support.

8. A car having a dump opening, a door for controlling said opening, and which is pivotally supported at one end and movable endwise, a shaft having connection with said door and by which the door may be elevated, a rigid support by which said door

is upheld in an elevated position, and means for moving said door endwise into position to be upheld by said rigid support; said last named means comprising a pinion carried by said shaft, and a rack carried by said door adapted to be engaged by said pinion after the door has been lifted.

In testimony whereof, I have hereunto affixed my signature, this 18th day of November, 1909.

PAUL BATEMAN.

In the presence of—

E. B. LINN,

A. J. McCauley.
